THE NORRIS PETERS CO., PHOTO-LITHO., WASHINGTON, D. C.

UNITED STATES PATENT OFFICE.

JOSEPH FRIEDRICH'S, OF ST. LOUIS, MISSOURI.

ART OF CROWNING FLOOR-JOISTS AND APPARATUS THEREFOR.

SPECIFICATION forming part of Letters Patent No. 487,406, dated December 6, 1892.

Application filed May 2, 1892. Serial No. 431,480. (No model.)

To all whom it may concern:

Be it known that I, JOSEPH FRIEDRICH'S, a citizen of the United States, residing in the city of St. Louis and State of Missouri, have 5 invented certain new and useful Improvements in the Art of Crowning Floor-Joists and Apparatus Therefor, of which the following is a full, clear, and exact description.

My invention relates to the method of and 10 means for giving to floor-joists the required curvature or convexity to their upper surfaces to compensate for their sag when placed in position and made to support a weight or strain, and has for its object to give each 15 joist in a group of joists to be used together a crowning corresponding to and compensating for their different relative strengths and consequent different relative sags when subjected to a given load or strain, adapting 20 the top surfaces of the different joists to be brought to a common level when thus subjected to such strain or load.

The object in any case of crowning joists is to give the upper surface a convexity or 25 curvature more or less pronounced from end to end to compensate for the normal sag of the same when supported as a beam at either end. The degree of curvature thus given is determined by the length and should also be 30 modified in each particular piece to independently compensate for the relative deflection resistance of each piece. Heretofore this has been done by hand, the curvature given to the upper surfaces of the joists being uniformly gaged by a templet similar for all 35 joists of the same length. It is evident that by this method the joists are all similarly curved and that when placed in position, supported at their ends, the weaker ones will 40 have more of a sag than the stronger ones, leaving the upper floor-supporting surfaces uneven and irregular.

My invention consists in an improved method of crowning joists by which the unequal 45 vertical beam strength of different timbers is provided for, as hereinafter described.

The accompanying drawings, in which like numbers of reference denote like parts in the several figures, serve to illustrate my improved method and one form of apparatus adapted to put the same into practice.

The machine illustrated is a simple wood-

planing machine with a longitudinally-movable bed on which to support the timbers to be planed and bring them under the rotating 55 planer-knives, as in an iron-working planer.

Figure 1 is a side elevation of the same. Fig. 2 is a plan view. Figs. 3 and 4 are side elevational views of a joist being planed and after having been planed, respectively; and 60 Fig. 5 is a cross-section taken on the line 5 5 in Fig. 4. Fig. 6 is a vertical section taken parallel to the length of the machine through the rollers and cutter-head, showing the spring-bearings for the rollers in elevation. 65 Fig. 7 is a vertical cross-section on line 7 7 in Fig. 6, and Fig. 8 is a longitudinal section on line 8 8 in Fig. 6. Figs. 9 and 10 are views similar, respectively, to Figs. 2 and 1, showing the preferred details of the bearings for 70 the presser-rollers than what is shown in Figs. 1 and 2.

11 are the side timbers of the machine, to which are secured the vertical standards 2 and in which are formed guideways for the 75 sliding bed-plate 3. In the standards 2 are formed guides for the sliding frame 4, which is vertically adjustable by means of the screws 5, one of which is placed on either side of the machine and which are connected together 80 by a cross-shaft 6 (see Fig. 1) and bevel gear-wheels 7, so as to operate both the ends of the frame 4 together. In the frame 4 are revolubly mounted the forward and following rollers 8 and the rotary knife-shaft 9, to the 85 end of which, as shown in Fig. 2, is secured the small drive-pulley 10, by which means the machine as a whole is made to operate through the medium of the belt 11. It will be readily understood without more detailed 90 illustration that in the operation of the machine at the same time that the knife-shaft 9 is made to rotate the bed-plate or platform 3 is given a longitudinal movement to bring the joists 12 in operative position under the 95 rotating knives.

The foregoing description relates to the form of machine illustrated in the first and second figures in the drawings. While by the use of the machine as just described and as 100 illustrated in the first two figures the "crowning," as hereinafter described, can be effectively carried out, yet the details illustrated in Figs. 6 to 10, inclusive, and hereinafter de-

scribed are preferably made use of to more conveniently and, strictly speaking, more effectually carry out my method in practice. These details, indeed, are common to machines to which my method is adapted and form no part of this invention, but are preferably made use of in the practice of my improved method.

The rollers 8 are journaled in boxes 16, 10 which are provided guideways in the vertically-movable frame 4, the boxes being held in vertically-yielding position by the compression-springs 17 and 17', and this position made adjustable by means of the adjusting-screws 18, which bear against the upper end of the upper spring 17. The normal position of the journal-bearing is in this manner determined as a position of equilibrium between the two springs, and this decided by the tension given to the upper springs by the set or adjusting screws 18. By these means the level of the under or effective side of the rollers 8 and the cutting-level of the cutter 9 are adjustable relative to each other. The cut taken 20 by the knife is in any instance therefore defined, primarily, by the set position of the forward roller 8. Thus when the supporting-frame, is screwed down to bear harder on the timbers or, what is the same thing, the timbers press harder on these rollers, as herein-after explained, in the act of planing the upper spring will give more or less and the cutter will take a deeper "bite."

As illustrated, there are preferably (for economic reasons) several (six) joists 12 placed on the sliding platform 3 and secured together by the clamps 13. Instead of laying the joists flat on the plane surface of the sliding platform 3 I interpose under each end of the joists 40 a block 14 thick enough to raise the joists far enough away from the surface of the planer-bed or platform 3 when the joists are carried in under the action of the knife to be planed, as illustrated in Fig. 3, to allow for the necessarily-consequent deflection of the middle portions of the joists. This result might also be obtained by hollowing the bed of the planer to similarly allow for the deflection of the joists. In this manner the joists—in fact, each 50 individual joist independently of the other—are in the operation of crowning subjected to a strain similar to that when placed in a building, similarly applied, and under exactly similar conditions—*i.e.*, the ends only supported.

55 As already stated, the amount of cut of the knife 9 is due, primarily, to the relative position of the cutter-blades and the normal position of the forward roller 8, but not altogether so. When, for instance, in the act of 60 planing the frame 4 is screwed down, so that the ends of the timbers, when they are supported at their ends only, are immediately below the cutter-head, the roller is forced upward relative to the cutter, and therefore the 65 cut taken will be greater at this point than at the middle when it comes under the cutter in that the timbers give and do not press so

hard against the rollers 8, allowing them by the action of the upper springs 17 to be depressed relative to the cutter.

70

It will be evident that the curved form of surface of the upper edge of the joists illustrated in Fig. 4 will be the result of passing the joists in under the knife and rollers in that, the ends being supported, the knife will 75 take out a given cut there, which cut will be reduced as we approach the middle portion of the length of the joists, the joists being deflected from the normal by the pressure applied in a vertical direction by the knife and rollers, or, what is the converse of this fact, if the joists were rigid beams without deflection the cut would be even throughout the length of the same. Moreover, this decrease of cut at the mid-length of the timbers being 80 due to the deflection of the joists as beams supported at each end for a given pressure, the stronger ones—*i.e.*, those better able to resist this applied strain—will give less and be cut more in the middle—that is, they will be cut 85 more nearly to a straight line—than the weaker ones, which give more to the applied strain. There is more than one cause that goes to effect this result. As before stated, the primary cause of the crowning of the 90 group of joists, considered collectively, is due to the decrease of upward pressure of the joists in their mid-length on the presser-rollers; but this in itself does not account for the differential planing of individual weaker 95 and stronger timbers. Consider, for the sake of illustration, the pressure-rollers removed. Then, the cutter itself bearing against the upper surfaces of the joists, as they are supported at their ends only, the joists will give more 100 or less before the revolving knife, and that in each individual joist in the inverse proportion to its strength and its ability to resist the deflecting strain put upon it by the cutter—that is, at the middle of their length 105 they will be cut less than at their ends, and that to a different degree as between weaker and stronger ones. Now when the roller (the preceding one, which is the only one that need 110 be considered) is used the strain is partly 115 borne by the roller and partly by the cutter, and, while the result, as above, when the roller was removed, will not be so marked, yet it is effected to a comparative degree. It has also been observed in the practical use of the 120 planer as described, where the roller is small—not more than two and one-half or three inches in diameter—it becomes more or less, in proportion to the pressure put upon it, embedded in the fiber of the timber, and this 125 of course, modified by the strength of the individual joist, in this manner presenting more timber to the cutter than if it was not embedded and of course comparatively more for the stronger timbers. Now when this applied 130 strain is removed and the joists allowed to assume their normal position their upper surfaces at their mid-lengths will be brought to relatively different heights, the weaker ones,

as shown in Fig. 5, those which were less able to resist the deflecting strain put upon them in the planer, being the higher. When this strain is again applied, as would be the case

5 when the joists are put into service, as to support a floor, they will be again brought to a common level. It is evident that when the joists are supported at their ends only they at once assume a normal position of deflection due to their own weight and that this enters into and is compensated for by the method described, especially inasmuch as they are placed during the act of crowning in their natural position—the one in which 15 they are to be used. This natural deflection also undoubtedly helps in a small measure to obtain the results effected.

It is in this particular that I claim the superiority of my improved method in practical results over any in use heretofore—in that the joists are planed to a flat surface when they are being subjected to what can be considered conditions exactly similar to what they would be subjected when used in actual 25 practice.

It will be evident that, while, as already stated, the essential feature of invention in the apparatus used to carry out my method is the supporting of the joists at their ends 30 only, these details relate merely to this particular means of carrying my method into practice—that is, when the deflecting pressure is applied by the means itself by which the surface of the joists is planed or leveled 35 off it is enough to support the joists in such a position to allow these forces to act. The principal being disclosed, it is obvious that other means might be devised to effect the results obtained. For instance, the joists 40 might be deflected by means other than the presser-roller and the cutter and means other than the revolving cutter be used to level the surface while the joists are thus deflected.

I claim—

45 1. The method herein described for crowning

ing floor-joists, which consists in subjecting the same to a deflecting strain and leveling one surface while so subjected, substantially as and for the purposes described.

2. The method herein described for crowning floor-joists, which consists in supporting the same at their ends and planing or otherwise leveling the upper surfaces of the same, substantially as and for the purposes described. 50

3. In a machine for crowning floor-joists, the combination, with the leveling-cutter, of a supporting and carrying platform and means for deflecting the stock while it is being operated on by the cutter, substantially as and for the purposes specified. 55

4. In a machine for crowning floor-joists, the combination, with the cutter, of a supporting and carrying platform and means supported directly by and carried with the 60 platform by which the joists are supported at their ends only, substantially as and for the purposes specified. 65

5. In a machine for crowning floor-joists, the combination, with an adjustable cutter, 70 of a supporting and carrying platform provided with means for supporting the stock away from the platform, thereby permitting the joists to be deflected while being cut, substantially as and for the purposes specified. 75

6. As a new article of manufacture, a crowned floor-joist bellied on one side, said bellied portion being formed by planing or otherwise leveling one surface of the joist while it is being deflected from the normal, 80 substantially as and for the purposes specified.

In testimony whereof I have affixed my signature, in presence of two witnesses, this 27th day of April, 1892.

JOSEPH FRIEDRICH.
